UNITED STATES PATENT OFFICE.

ANDREW KENDECHY, OF CLEVELAND, OHIO.

LOCK.

1,415,651.

Specification of Letters Patent. Patented May 9, 1922.

Application filed June 15, 1920. Serial No. 389,167.

To all whom it may concern:

Be it known that I, ANDREW KENDECHY, a citizen of the United States, residing at Cleveland, in the county of Cuyahoga and 5 State of Ohio, have invented new and useful Improvements in Locks, of which the following is a specification.

This invention relates to improvements in combination locks and has for an object the 10 provision of a lock of this type which is simple in construction and which may not be opened by persons unfamiliar with the combination.

Another object is the provision of a combination lock which includes indicia carrying 15 dials or disks, means being provided for rearranging or transposing the indicia characters, whereby the combination may be changed.

20 With the above and other objects, in view, the invention further includes the following novel features and details of construction, to be hereinafter more fully described, illustrated in the accompanying drawings 25 and pointed out in the appended claim.

In the drawings:

Figure 1 is an elevation of a lock embodying the present invention.

Figure 2 is an enlarged transverse section 30 with the parts in position to permit of the retraction of the locking bolt.

Figure 3 is a view similar to Figure 2, with the parts in locked position, or in position whereby the operation of the locking 35 bolt will be prevented.

Figure 4 is a section on the line 4—4 of Figure 2.

Figure 5 is a plan view of one of the 40 indicia carrying disks with certain of the indicia blocks removed.

Referring to the drawings in detail, wherein like characters of reference denote corresponding parts, the reference character 10 indicates a lock casing which is preferably 45 of rectangular shape and which is open at one side and provided with a cover or closure plate 11, the latter being secured to the casing 10 in any suitable manner and provided adjacent to its upper edge with a centrally disposed indicating arrow 11'.

The casing is provided with a central opening 12, while the cover plate 11 is provided with an opening 13 whose diameter is larger than the opening 12.

Extending from the opening 12 in the casing 10 and the opening 13 in the closure plate is a hollow cylindrical member 14. One end of this member is provided with a flanged head 15 which bears upon the outer face of the casing 10, while the opposite end 60 of the member 14 is closed by a threaded cap 16.

Mounted for sliding movement within the casing 11 is a locking bolt 17 which is capable of being projected beyond the end of 65 the casing for engagement with a suitable keeper, (not shown) and of being retracted within the casing. For the purpose of operating this bolt there is provided a disk 18 which is mounted upon the hollow cylindrical member 14 and is capable of rotation 70 thereon. This disk is provided with a lug 19 having a slot formed therein which receives a pivot carried by the bifurcated end of the shank 20 of the locking bolt 17. Thus, 75 a movement of the disk 18 will actuate the bolt 17.

Also mounted upon the hollow cylindrical member 14, and upon the outside of the casing 10 and capable of rotation on the 80 said member are disks 21. Any desired number of these disks may be employed. In the drawings, two of the disks 21 are shown and these disks are provided upon their marginal edges with indicia which may be in 85 the form of either numbers or letters or both. This indicia is preferably carried by blocks 22 which are removably secured to the disks 21, the purpose being to permit the blocks to be transposed or rearranged to 90 effect a change of the combination. The disks 21 are provided with transversely disposed notches 23, while the disk 18 is provided with a notch 24.

Mounted within the hollow cylindrical 95 member 14 is a sectional rod 25, the adjacent ends of the sections being connected by an oval shaped spring 26 which is arranged transversely within the member 14. One end of the sectional rod 25 is provided with 100 a head 27, while the opposite end is provided with a knurled knob 28. Secured to the bowed spring 26 is a dog 29 which is adapted to operate through a slot 30 arranged longitudinally of the hollow cylindrical member 14 so as to permit the dog to 105 engage the notches 23 and 24 of the disks 21 and 18 respectively. When thus engaged the

bolt 17 may be operated by rotating the hollow cylindrical member 14.

In the operation of the lock, assuming that the parts are in position to prevent the operation of the locking bolt, the disks 21 are rotated to bring the proper numbers or letters upon their edges into proper register with the arrow on the plate 11 so as to register the notches 23. These disks are then rotated simultaneously until the notches 23 therein register with the slot 30 in the hollow cylindrical member 14. A slight outward movement of the dog 29 will then occur so that the member and disks 21 will be locked together. This initial engagement is due to the irregular outer edge 29^a of the dog 29. The rotation of the member 14 is then continued until the slot 30 and notch 24 of the disks 18 register, whereupon the dog will be forced outward under the action of the spring 26 to engage the notch in the disk 18 so that all of the disks and the member 14 will then be locked together. The locking bolt 17 may then be operated by revolving the member 14.

In order to disengage the dog 29 from the disks, the knurled knob 28 is drawn outward so that the dog will be retracted within the slot 30, whereupon the disks 21 may be revolved independently. When it is desired to change the combination certain of the blocks 22 may be transposed so that their numbers or characters will indicate registration of the notches of the disks.

The invention is susceptible of various changes in its form, proportions and minor details of construction and the right is herein reserved to make such changes as properly fall within the scope of the appended claim.

Having described the invention what is claimed is:—

A device of the class described comprising a casing provided with a central opening a cover plate having on opening of a greater diameter than the opening in said casing and provided with an indicating arrow, a hollow cylindrical member extending through the openings in said casing and said cover and provided with a longitudinally extending slot, a flanged head extending from one end of said member and engaging said casing, a threaded cap removably secured to the opposite end of said member, a locking bolt mounted for sliding movement within the casing and provided with a shank having bifurcated ends, a disk rotatably mounted upon said cylindrical member, having a notch formed therein and provided with a slotted lug pivotally secured to the bifurcated end of the shank of said lock bolt, a plurality of disks rotatably mounted upon said cylindrical member upon the outside of said casing provided upon their marginal edges with indicia and having notches formed therein, a sectional rod located in said hollow cylindrical member and extending through said head and said cap, an oval shaped spring secured to the adjacent ends of the sections of said rod, a knurled knob secured to one end of said rod, said sectional rod at the opposite end thereof engaging the head of said cylindrical member, and a dog secured to said spring and adapted to engage the notches in said disk.

In testimony whereof I affix my signature.

ANDREW KENDECHY.
